CLAIM

The ornamental design for a set of fish toys, as shown and described.

DESCRIPTION

FIG. 1 is a bottom, rear and right perspective view of the first fish component of the set of fish toys showing my new design;

FIG. 2 is a top, front and left perspective view thereof;

FIG. 3 is a bottom, right and rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a top, left and front perspective view of the second fish component of the set of fish toys showing my new design;

FIG. 11 is a bottom, right and rear perspective view thereof;

FIG. 12 is a top, rear and right perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a top, left and front perspective view showing the design components in a first configuration of use; and,

FIG. 20 is a top, rear and right perspective view showing the design components in a second configuration of use.

The broken lines in the drawings depict environment of the fish toys that form no part of the claimed design.
